HARRY HAVEN, OF BALTIMORE, MARYLAND

FLUID-MIXING DEVICE

Application filed April 1, 1930. Serial No. 440,780.

This invention relates to improvements in devices for mixing or commingling fluids, it being especially an improvement on the mixing device disclosed in the patent to Crocker 5 H. Sanford, 1,328,204 granted January 13, 1920, and it consists of the constructions, combinations and arrangements herein described and claimed.

An object of the invention is to provide a 10 mixing device which embodies as an important part thereof a certain mixing valve by which a jet or stream of gas is ejected into a jet or stream of water in a direction opposite thereto so that the resulting furious 15 turbulence will produce a most intimate mixture of the two constituents to the ultimate benefit of a certain fluid-mixing apparatus of Harry Haven, filed April 1, 1930, Serial No. 440,779, with which the instant device is intended to be used.

Other objects and advantages will appear in the following specification, reference being had to the accompanying drawings in which

Figure 1 is a vertical section of the improved fluid-mixing device, parts being shown in elevation.

Figure 2 is a cross section taken on the line 2—2 of Figure 1 particularly showing how the walls of the mixing chamber act as a stop 30 for the nozzle of the mixing valve, thus insuring the exactly central location of the gas orifice.

Figure 3 is a detail sectional view taken substantially on the line 3—3 of Figure 1, 35 illustrating the approximate paths of the gas and water through the region of turbulence in the mixing chamber.

The mixing device 1, or mixer as it may variably be called, comprises a reservoir 2 and a mixing valve 3 by which water conducted from a source of water by a pipe 4 and gas conducted for a source of carbonic acid gas by a pipe 5 are mixed, the fluid mixture being temporarily stored in the reservoir 2 45 until an appropriate control (not shown) of a discharge conduit 6 is opened.

A mixing chamber 7 forms part of and is in communication with the reservoir 2. It is at the water inlet to this chamber that a 50 back check valve casing 8 is connected, the

ball valve 9 of which it adapted to prevent the retrogression of carbonated water into the pipe system of the soda fountain, dwelling, etc. where the installation is made.

The mixing valve 3 has a stem 10 with a 55 needle end 11 which is adjustable in reference to the nozzle 12 by virtue of the adjustments of the stem in a gland 13. Contrary to the customary arrangement of needle valves the extremity of the nozzle 12 is closed. The gas 60 orifice 14 is arranged radially of the bore 15 so as to open laterally of the nozzle or at one side.

This disposition of the orifice has an important bearing on the invention and on the 65 effectiveness of the fluid-mixing apparatus with which the mixing device is intended to be used. It is observed in Figure 1 that the orifice 14 is in direct opposition to the water passage defined by the pipe 4 and the bore of 70 the valve casing 8. The gas and water jets or streams, both of which are under pressure, will thus oppose each other and produce a 75 furious turbulence in the region of confluence 16 (Fig. 1).

The action will be approximately as indicated by the tortuous arrows in Figure 3. Gas ejected as designated by the arrows 17 will meet the stream of water designated by arrows 18. The two fluids will tend to merge 80 as designated by arrow 19 and, by virtue of the presence of the nozzle 12 in the mixing chamber 7 will be diverted as at 20 until they strike the walls of the mixing chamber. A deflection of the fluids both at the walls of 85 the mixing chamber and the walls of the nozzle 12 will carry them around as designated by arrows 21 so that they will cross the streams designated both by the arrows 19 and 20 as well as themselves before finally passing 90 up the sides and front of the nozzle 12 on the way to the reservoir 2.

It is the combining of the two fluids and the causing of their deflection and crossing 95 as well as recrossing of their mutual paths in the rather constricted space of the mixing chamber 7 that results in that turbulence of the gas and water constituents that will bring about a most intimate mixture. It may be explained that the thorough commingling 100

of the water and carbonic acid gas is of utmost importance to the treatment of certain ailments, for example rheumatism, for which the apparatus is adapted.

5 If the mixture were "spotty", that is to say so imperfect that a given quantity of the mixture contained larger volumes of gas in certain regions than in others, the effectiveness of the mixture would be greatly minimized for the particular use just mentioned. 10 But by driving the two jets or streams against each other in direct opposition to the directions of their paths a tremendous swirling action is set up in a very restricted space 15 with the inevitable result of a thorough mixture of the constituents.

The manner in which the orifice 14 is located exactly on the axial center of the mixing chamber 7 is as follows:—A portion of the 20 nozzle 12 is threaded at 22 to permit its being screwed into the side of the mixing chamber 7. The internal diameter of the mixing chamber as well as the external diameter of the nozzle 12 will be so apportioned that 25 when the inward screwing of the nozzle 12 is stopped by contact of the lateral corners 23 of the nozzle with the walls of the mixing chamber (Fig. 2) the orifice 14 will stand in the exact position depicted in Figure 1. The 30 contact of the nozzle 12 with the walls of the mixing chamber thus constitutes a gauge to the position of the orifice 14. In addition to this the engagement of the nozzle with the walls of the mixing chamber tends to stabilize the mixing valve. The free end of 35 the nozzle is thus supported by the walls of the mixing chamber, and the rather high fluid pressure to which it is subjected will have little effect on tending to loosen the mixing valve.

40 The operation is as follows:—It is to be understood that the mixing device will be used in conjunction with the fluid-mixing apparatus of the application previously mentioned. This, however, is not to be regarded as a restriction because the instant mixing device might be used in other connections.

45 Upon opening the control device (not shown) which will be associated with the discharge conduit 6, the resulting flow of fluid will be accompanied by an inflow of water at the pipe 4. The same opening of the control device causes an inflow of gas at the pipe 5. The two fluids mix in the region 16 (Fig. 51) in the manner already fully explained (Fig. 3) so that the reservoir 2 is temporarily stopped with the mixture prior to its discharge at the pipe 4.

60 While the construction and arrangement of the improved fluid mixing device is that of a generally preferred form, obviously modifications and changes may be made without departing from the spirit of the invention 65 or the scope of the claims.

I claim:—

1. A fluid-mixing device comprising a normally closed reservoir having a communicating mixing chamber, means for introducing liquid into the chamber in the direction of the reservoir, and means for introducing a jet of gas into the chamber in the direction opposite to that of the liquid jet, thus to produce a mixture for storage in the reservoir.

75 2. A fluid-mixing device comprising a mixing chamber, means for introducing a jet of liquid in one direction at one end of the chamber, and a mixing valve having a nozzle fitted in one side of the chamber with a radial orifice axially alined with the chamber and 80 so opening as to discharge a jet of gas into the chamber in opposition to the liquid jet.

85 3. A fluid-mixing device comprising a mixing valve having a nozzle with a radial orifice opening at one side of the nozzle to discharge a jet of gas in one direction, a mixing chamber into the side of which the nozzle is projected until the corners of the nozzle engage adjacent portions of the wall of the chamber thus establishing the orifice in line 90 with the axis of the mixing chamber, and means for introducing liquid into the chamber in the direction opposite to that of the gas jet and producing a region of confluence between the nozzle and said liquid inlet means. 95
